PAPER HAT

Irving Gardner, Brooklyn, N. Y.

Substitute for abandoned application Serial No. 563,835, November 17, 1944. This application August 8, 1945, Serial No. 609,542

8 Claims. (Cl. 2—195)

1

This invention relates to new and useful improvements in a paper hat.

This is a substitute for my abandoned application, filed on November 17, 1944, Serial Number 563,835.

More specifically, the present invention proposes the construction of a paper hat characterized by having a visor, a rim and a top, all formed of a single sheet of heavy paper or cardboard and held together without the employment of any means not forming an integral part of the sheet.

Still further it is proposed to provide a hat as aforesaid in which the top is roughly elliptical in shape and the hat is open throughout the major portion between the rim and top.

Another object is to provide a hat of the aforesaid type having a single connecting member between the rim and top in the back of the hat and another single connecting member between the visor and top in the front of the hat.

A further object is to provide a hat of the aforesaid type having a single connecting member between the rim and top in the back of the hat and two spaced connecting members between the visor and top in the front of the hat.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a hat constructed in accordance with this invention.

Fig. 2 is a plan view of the blank of paper from which the hat of Fig. 1 was made.

Fig. 3 is a fragmentary rear view of the hat.

Fig. 4 is a view similar to Fig. 1 of a hat constructed in accordance with a modification of this invention.

Fig. 5 is a plan view of the blank of paper from which the hat of Fig. 4 was made.

The hat 10, shown in Figs. 1-3, according to this invention, comprises a visor 11 rounded at its front and having two depending wings 12 at its sides. The rear edge 13 of the visor is curved. The hat also has a top 14, substantially elliptical in shape and connected to the visor by two spaced bars 15, the top 14 having a curved extension 14a between the bars 15 which shades the forehead of a person wearing the hat. At the rear of the top 14 depends a support 16 having two cuts 17. The hat has a rim 18 formed by two bars extending rearwardly from the wings

2

12 and attached to the support 16 by passing through the slots 17 as is clearly shown in Fig. 3.

In order to construct the hat, a sheet of heavy paper or cardboard is cut, by one operation by a suitable die, into the blank shown in Fig. 2. A great many blanks may be cut by one operation, thus enabling mass production of the paper hats. The wings are then formed by bending on the lines a, the bars 15 are bent at the bottom lines b and the top lines c, thus elevating the top 14 above the visor, and the support 16 is bent along the line d. The ends of the two members forming the rim 18 are then secured to the support 16 by passing them through both slots 17.

The hat thus constructed has many advantages over other previously known paper hats. It is open between the rim and top for the passage of air therethrough for cooling the wearer of the hat. It is made entirely of one piece of cardboard, so that the blank can be formed by one operation, and there are no separate pieces of the hat to become lost. Thus it may be handled easily, especially by vendors selling the hats at beaches, ball games and similar places where paper hats are needed to shade the head from the sun.

The slots 17 are made just long enough to receive the members of the rim 18 so that once 30 they are passed through the slots, they are gripped, preventing them from being pulled out. The size of the rim can be quickly and accurately adjusted to fit the wearer's head by moving the members of the rim in the slots 17 against the 35 friction of the grip thereof. If desired, the hat may come equipped with a flap of glued paper 19, shown in Fig. 3, which may be moistened and folded down to adhere to and secure both members of rim 18 in the slots 17.

40 A feature of the hat 10 is that it has two bars 15, one on either side of the top 14, thus insuring a strong support of this top on the visor 11.

The hat 10' shown in Figs. 4 and 5, constructed 45 in accordance with a modification of this invention, is of the same type as the hat 10 but distinguishes therefrom by having a single central bar 15' connecting the top 14' to the visor 11'.

While I have illustrated and described the preferred embodiments of my invention, it is to be understood that I do not limit myself to the precise constructions herein disclosed and the right is reserved to all changes and modifications coming within the scope of the invention as defined in the appended claims.

55 Having thus described my invention, what I

claim as new, and desire to secure by United States Letters Patent is:

1. A paper hat formed entirely from a single blank of paper comprising a visor, a rim formed of two members, each integral at one end with said visor at one side thereof and free at the other end, a top, a bar connecting said top with said visor and integral with both said visor and top, and a support integral at one end with the rear of said top and having two spaced slots adjacent its other end, said free ends of said members both passing through both of said slots.

2. A paper hat formed entirely from a single blank of paper comprising a visor, a rim formed of two members, each integral at one end with said visor at one side thereof and free at the other end, a top, a bar connecting said top with said visor and integral with both said visor and top, and a support integral at one end with the rear of said top and having two spaced slots adjacent its other end, said free ends of said members both passing through both of said slots, said bar being at the center of said visor and top.

3. A paper hat formed entirely from a single blank of paper comprising a visor, a rim formed of two members, each integral at one end with said visor at one side thereof and free at the other end, a top, a bar connecting said top with said visor and integral with both said visor and top, and a support integral at one end with the rear of said top and having two spaced slots adjacent its other end, said free ends of said members both passing through both of said slots, said slots being only slightly longer than the width of said members thereby gripping said members and resisting movement of said members from said slots.

4. A paper hat formed entirely from a single blank of paper comprising a visor, a rim formed of two members, each integral at one end with said visor at one side thereof and free at the other end, a top, a bar connecting said top with said visor and integral with both said visor and top, and a support integral at one end with the rear of said top and having two spaced slots adjacent its other end, said free ends of said members both passing through both of said slots, said top having a curved extension at its front end.

5. A paper hat formed entirely from a single

blank of paper comprising a visor, a rim formed of two members, each integral at one end with said visor at one side thereof and free at the other end, a top, a bar connecting said top with said visor at each side of said top and integral with both said visor and top, and a support integral at one end with the rear of said top and having two spaced slots adjacent its other end, said free ends of said members both passing through both of said slots.

6. A paper hat formed entirely from a single blank of paper comprising a visor, a wing integral with and depending from each side of said visor, a rim formed of two members, each integral at one end with one of said wings and free at the other end, a top, a bar connecting said top with said visor and integral with both said visor and top, and a support integral at one end with the rear of said top and having two spaced slots adjacent its other end, said free ends of said members both passing through both of said slots.

7. A paper hat formed entirely from a single blank of paper comprising a visor, a wing integral with and depending from each side of said visor, a rim formed of two members, each integral at one end with one of said wings and free at the other end, a top, a bar connecting said top with said visor and integral with both said visor and top, and a support integral at one end with the rear of said top and having two spaced slots adjacent its other end, said free ends of said members both passing through both of said slots, said visor having an inner curved edge adapted to fit a person's forehead.

8. A paper hat comprising a visor, a rim formed of two members each integral at one end with said visor at one side thereof and free at the other end, a top, a bar connecting said top with said visor and integral with both said visor and top, a support integral at one end with the rear of said top and having two spaced slots adjacent its other end, said free ends of said members both passing through both of said slots, and a glued paper flap partially glued to said support and having a portion overlapping said members adjacent said slots for securing same to said support.

IRVING GARDNER.
